(57) **CLAIM**

The ornamental design for an LED luminaire, as described and shown.

DESCRIPTION

FIG. 1 is a perspective view a lower side of an LED luminaire;

FIG. 2 is a perspective view of an upper side of the LED luminaire shown in FIG. 1;

FIG. 3 is a side view of the LED luminaire shown in FIG. 1;

FIG. 4 is a side view, opposite the view shown in FIG. 3, of the LED luminaire shown in FIG. 1;

FIG. 5 is an enlarged end view of the LED luminaire shown in FIG. 1;

FIG. 6 is an enlarged end view, opposite the view shown in FIG. 5, of the LED luminaire shown in FIG. 1;

FIG. 7 is a bottom view of the LED luminaire shown in FIG. 1; and,

FIG. 8 is a top view of the LED luminaire shown in FIG. 1.

The broken lines showing environmental structure are for illustrative purposes only and form no part of the claimed design. The separation and bracket indicate that the precise length of the LED luminaire is not claimed.
